US00D966824S

(12) **United States Design Patent** (10) **Patent No.:** **US D966,824 S**
(45) **Date of Patent:** **** Oct. 18, 2022**

(54) **COOLER BOX**

(71) Applicant: **GLOBERIDE, Inc.**, Tokyo (JP)

(72) Inventor: **Hiroshi Yagi**, Toyko (JP)

(73) Assignee: **GLOBERIDE, Inc.**, Tokyo (JP)

(**) Term: **15 Years**

(21) Appl. No.: **29/763,272**

(22) Filed: **Dec. 22, 2020**

(30) **Foreign Application Priority Data**

Jun. 25, 2020 (JP) ..... 2020-012809 D

(51) **LOC (13) Cl.** **07-99**

(52) **U.S. Cl.**

USPC **D7/607**; D3/327

(58) **Field of Classification Search**

CLAIM

The ornamental design for a cooler box, as shown and described.

DESCRIPTION

FIG. 1 is a top, rear, left side perspective view showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The lightened portions of the cooler box shown in FIGS. 1-7 illustrate environment and form no part of the claimed design.

1 Claim, 6 Drawing Sheets
